ABSTRACT OF THE DISCLOSURE

A torque measuring wrench in which the relative angular displacement of the opposite ends of a torque-transmitting member is transmitted to a torque-indicating arm pivotally mounted on the member and extending along the length of the member.

This invention relates to torque wrenches and, more particularly, to an improved torque-measuring wrench in which the effect of applied torque to the wrench is substantially magnified in order to yield an accurate reading of applied torque.

Torque-measuring wrenches are well-known in the art. The usual torque wrench comprises an elongated arm having a standard square drive element at one end. The torque-indicating means associated with the elongated arm may comprise gearing or a rack and pinion arrangement or even spring steel strips, the purpose of which is to move a pointer to indicate the applied torque.

Variations of such torque-measuring apparatus are known in which the indicating device is separated from the handle. Such variations often involve gearing or other complex indicating linkages combined with a large dial face and pointer. The dial face and pointer usually extend laterally from the torque device, thus making the entire arrangement clumsy to handle and easily damaged.

The present invention is designed to provide a compact, easily used, accurate torque-measuring wrench. The present construction utilizes a novel elongated torque-indicating member which substantially magnifies the relative angular displacement of the opposite ends of the torque-transmitting member or rod upon which the torque-indicating member is carried.

In its narrower scope, the present invention includes a torque-indicating collar which is moved by the torque-indicating member and which includes a calibrated scale marked upon it for a direct reading of applied torque. The preferred embodiment combines a torque-transmitting rod, a collar rotatably mounted at one end of the torque rod, an elongate torque-indicating member engaged with the collar and pivotally mounted at the opposite end of the torque rod and an arm secured to the torque rod near the collar and extending along the torque-transmitting member and having its opposite end coupled to the torque-indicating member for moving the torque-indicating member and the collar coincidentally with angular displacement of the opposite ends of the torque rod resulting from the application of torque thereto.

In the drawing, FIG. 1 is a front elevational view of the torque wrench in partial section and FIG. 2 is another elevational view of the wrench also in partial section, taken along the line 2—2 of FIG. 1.

FIG. 3 is a detail of the work-engaging end of the wrench.

Referring now more particularly to the drawing in which similar characters of reference represent corresponding parts in each of the several views, the torque wrench is shown generally in FIG. 1. The torque-transmitting member or rod 10 has a standard square drive element 12 on one end adapted to engage a wrench socket in order to exert torque on a bolt head or other work (not

2

shown). The opposite end is formed with a square recess 14, adapted to receive the drive element of a torque-transmitting handle. The drawing shows a universal joint drive 16 received in the recess 14. A torque-transmitting handle would be then engaged in the universal joint for the application of torque to the wrench.

The recess 14 is formed in a cylindrical shoulder 18, on one end of the torque-transmitting rod 10. Rotatably mounted on the shoulder 18 is a torque-indicating collar 20 formed with a tab 22 having a radially oriented slot 24 therein, into which is engaged one end of the torque-indicating link 26.

The opposite end of the link 26 is formed with an enlarged base 28. The base 28 is mounted on a pivot 30, the pivot being affixed near the work engaging element 12, at the end of the torque-transmitting rod 10.

A rigid arm 32 is secured to the shoulder 18. The arm 32 extends along the torque-transmitting rod 10, terminating near the work engaging element 12. The end 34 of the arm 32 is positioned closely adjacent the pivot 30 although there is clearance between the end 34 of the arm and the lower shoulder 36 of the torque transmitting rod 10 to which the pivot 30 is affixed.

The end 34 of the arm 32 is provided with a ball 38 suitably mounted on a post 40. The ball is received within a complementary spherical recess within the base 28 of the indicating link 26.

As may be noted in FIG. 2, the center of the ball 38 received within the recess is offset from the axis of the pivot 30. The distance between the center of the ball and the pivot axis is quite small compared with the length of the link 26. Therefore, a relatively small angular displacement between the ends of the torque rod 10 is substantially magnified. This results in highly accurate readings of the applied torque.

In order to yield the most accurate indication of torque, indicator marks and scales are provided to show relative rotation of the shoulder 18 and the collar 20. Scale calibrations 42 are marked axially along the circumference of shoulder 18 and radially on the collar 20. Corresponding indicator markings 44 are cut into both the shoulder and the collar. The use of calibration scales and indicator markings on both the shoulder 18 and the collar 20 permits the user to note the readings from whatever position the scales are observed and no matter what position the torque handle may have with respect to the drive end of the torque wrench.

In FIG. 3 an alternate embodiment of the connection between the end 34 of the arm 32 and the link 26 is shown. The alternate comprises a pair of ball joints 46 one of which is affixed to the end 34 of the arm and the other to the end 48 of the torque-indicating link 26.

In operation, a wrench socket is affixed to the drive element 12. The socket will be suitable for the particular work piece such as a bolt, spark plug or the like. A drive handle (not separately shown) is attached to the wrench by placing its drive element in the recess 14 or in the recess of the universal joint 16 when the universal joint is in place. As torque is applied and the work piece tightened, there will be angular displacement between the driving and driven ends of the torque rod 10. This relative angular movement will cause the relative movement of the pivot 30 and the spherical portion 38 of the bolt joint as well. This in turn will cause movement of the link 36 which will itself rotate the collar 20.

The calibrations may be chosen so that a direct reading in foot-pounds may be made. The distance between the center of the ball 38 and the axis of the pivot 30 heretofore described varies according to the size of the particular torque wrench. Should a substantial magnification of the angular displacement of the ends of the torque-

transmitting rod 10 be desired, it is possible to decrease the distance between the center of the ball 38 and the axis of the pivot 30. Decreasing this distance will cause correspondingly greater rotation of the collar 20 for a direct reading of the applied torque. A light spring (not separately shown) is connected between the collar 20 and the torque rod 10 in order to reduce any play in the collar movement and make for more accurate readings.

These and other modifications of my invention may be practiced, it being understood that the form of my invention as described above is to be taken as a preferred example of the same. Such description has been by way of illustration and example for purposes of clarity of understanding. Various changes and modifications may be made without departing from the spirit and scope of my invention.

What is claimed is:

1. A torque-measuring wrench comprising: a torque-transmitting member having a first end adapted for work engagement and a second end adapted for engagement by a force transmitting tool; an arm secured to said second end and extended adjacent to and free from said first end; a collar rotatably mounted adjacent said second end; a link pivotally mounted on the torque member adjacent said first end and engaged with said collar; and a connection between the link and the free end of the arm for moving the link and thereby the collar when there is relative movement between the torque member and the free end of the arm.

2. The wrench of claim 1 and wherein the collar has a tab secured thereto, said tab having a slot wherein the link is engaged; and a scale marked on the collar and on the second end of the torque member, the scale calibrated so that upon application of torque to the member the position of the collar relative to the second end indicates the amount of applied torque.

3. The wrench of claim 1 and wherein the connection includes a ball joint, the center of rotation of said joint offset from the pivotal mounting of the link.

4. A torque measuring device comprising a torque-transmitting rod having a work engaging end and a force-transmitting element at the other end, a torque-indicating member extending along the torque rod, means for pivotally mounting said torque-indicating member at said work engaging end, and means for transmitting relative angular movement of the opposite ends of said torque-transmitting rod about the axis of said rod to said indicating member, said transmitting means including a connection between said force-transmitting element and said indicating member adjacent said pivotal mounting means.

5. The device of claim 4 and wherein said angular movement transmitting means comprises: a frame extending along said torque rod with one end of said frame secured to the torque-transmitting rod adjacent the force-transmitting element, and the other end of said frame free from and positioned close to said work engaging end and a coupling secured to the free end of said frame and engaged with the torque-indicating member at a location spaced from said pivotal mounting means.
